UNITED STATES PATENT OFFICE.

AUGUST J. MEYER, OF CHICAGO, ILLINOIS.

CUSHION-WHEEL FOR VEHICLES.

1,265,101.

Specification of Letters Patent.

Patented May 7, 1918.

Application filed May 6, 1916. Serial No. 95,950.

To all whom it may concern:

Be it known that I, AUGUST J. MEYER, a citizen of the United States, residing at Chicago, in the county of Cook and State of Illinois, have invented certain new and useful Improvements in Cushion-Wheels for Vehicles, of which the following is a specification.

My invention relates to a construction of cushion wheels for vehicles which is an improvement on the construction shown in my pending application Serial Number 715717, filed August 19, 1912, and in my present construction all of the practical advantages secured by my earlier construction are retained and improved devices are provided for mounting and housing the cushions.

My invention will be best understood by reference to the accompanying drawings in which—

Figure 1 is a side elevation of my improved vehicle wheel, part of the figure being in section to better show the cushion arrangement,

Fig. 2 is a sectional view through the parts shown in Fig. 1 taken along the line 2—2,

Fig. 3 shows a modified construction in which the resilient cushions shown in Fig. 1 are replaced by springs,

Fig. 4 shows an enlarged sectional view taken along the line 4—4 a part of the construction shown in Fig. 1,

Fig. 5 shows in side elevation a modified form of wheel construction for use with the cushion hub mechanism shown in Figs. 1 and 2,

Fig. 6 is a sectional view of the parts shown in Fig. 5 taken along the line 6—6,

Fig. 7 shows in elevation the spoke shown in section in Fig. 6,

Fig. 8 shows in side elevation the hub casting employed in the construction shown in Figs. 1 and 2,

Fig. 9 shows the construction of Fig. 8 in section taken along the line 9—9,

Fig. 10 shows in side elevation one of the cushions employed in Figs. 1 and 2, together with housing and protecting shoes.

Figs. 11 and 12 show in views similar to Fig. 1 a portion of modified hub construction in which different arrangements of cushioning devices are employed, and

Fig. 13 shows in a view similar to Fig. 4 a modified construction by means of which the cushions may be compressed in place

and given any desired degree of initial compression.

Similar numerals refer to similar parts throughout the several views.

As shown in Figs. 1 and 2 the wheel consists of a rim 15 provided with a tire 16 preferably of resilient material, this rim being secured to a ring 17 preferably of cast metal by sectors 18 riveted or bolted at 19 to flanges 20 projecting outwardly from the ring 17. A felly 15^a made in sections is preferably employed between the outer edges of the sectors 18 and the rim 15, all of the outer parts at their outer edges being held together by shrinking the rim in place. The ring 17 constitutes the outer portion of the hub construction, the inner part 21 of which is a metal casting supported in part by a sleeve 22 which carries bearings for rotatively mounting the wheel on its support. The sleeve 22 can of course if desired be rigidly secured to the axle instead of being rotatively mounted thereon.

The casting 21 has formed thereon at four equi-distant points cylindrical bosses 23, which form the supports for the inner cushion housing members 24, each of which members surrounds the major portion of two sides of a resilient cushion 25. Each member 24 is provided with a concave seat engaging the corresponding cylindrical boss 23 so that said member is positively held in place by said boss and yet permitted to rock somewhat thereon, there being a sliding action between the member and the boss for such rocking motion. The other two walls of each cushion compartment are formed by means of a member 26 resting against the inner surface of the ring 17 and also at one end against an arm 27 projecting axially from the plate 28 forming one of the side walls of the hub construction. There are four of these arms 27 and their faces adjacent the members 26 are disposed so that two adjacent arms constitute in effect a wedge carried by the casting 21 with which the plate 28 is integrally formed so that motion of the casting 21 relatively to the ring 17 in a direction to move the arms 27 away from said ring separates the adjacent members 26 somewhat and this exerts compression upon the cushions 25. A clearance space is provided between each pair of arms 27 through which an inwardly extending arm 29 projects radially from the ring 17 to engage a cushion bumper 30 supported

by the casting 21 between adjacent ones of the members 24. The ring 17 is also provided with inwardly projecting bosses 30^a equidistant from the arms 29, which bosses 5 are sufficiently large to have formed in them clearance openings 31 around the studs 32 projecting axially from the plate 28. An inclosing plate 33 is secured to the ends of the arms 27 and the ends of the studs 32 10 by cap screws 34 and 35 as indicated. Besides the bumpers 30 the casting 21 also carries a second pair of bumpers 36, each of which is indicated at the inner end of a boss 30^a. As a result of the construction 15 described it will appear that there are four bumpers employed which are equidistant from each other and spaced angularly at equal distances between the center radial lines of the cushions, these bumpers being 20 provided to limit the amount of radial motion that the ring 17 may have relatively to the casting 21. Any desired amount of clearance may be provided between the bumpers and coöperating bosses carried by 25 the ring 17, or if preferred no clearance at all may be used and the bumpers may be made of such material as to properly limit the radial motion referred to without said clearance.

30 The construction of the casting 21 and the relation of the disk or plate thereto, as well as the manner in which the arms 27 are formed thereon is best seen by reference to Figs. 8 and 9 which are similar to the construction shown in Figs. 1, 2 and 4 with the exception that the supporting tube 22^a is formed integrally with the casting and provided with inwardly extending angular flanges 37 which may readily be bored to 35 fit and be rigidly secured to the axle of the vehicle. In this construction a brake drum 38 is also shown as formed integrally with the casting 21^a.

At the base of each of the arms 29 an 45 axial hole 39 is made through the ring 17 to be engaged by circular plugs 40 as shown in Fig. 2, which plugs are rigidly secured to wearing plates 41 mounted upon and secured to the ring 17 between it and the plates 28 50 and 33. These wearing plates are provided with clearance openings around the tube 22 and around the arms 27 and the studs 32 so that the casting 21 and the parts carried thereby may move radially and angularly 55 relatively to said plates. Recesses 42 are formed in the inner faces of the plates 28 and 33 to contain lubricant to facilitate the free movement of the wearing plates relatively to the inclosing plates 28 and 33. Each 60 of the arms 29 may have holes 43 formed partly or wholly through its inner end if desired to somewhat lighten the construction.

It will be observed that the outwardly 65 extending ends of the members 24 diverge

outwardly from the radial line through the center of the adjacent boss 30^a, with which boss the outwardly diverging surfaces are in contact, as a result of which the boss 30^a acts as a wedge between the adjacent members 24 so that motion inwardly of the boss 30^a relatively to the casting 21 separates the members 24, causing them to rock somewhat upon the casting 21 and compress the corresponding cushions 25. It will be also 70 observed that angular motion of the casting 21 relatively to the ring 17 places alternate ones of the cushions 25 in compression so that the resultant of a load upon the axle and a turning movement thereon produces 75 a displacement of the axle relatively to the ring 17, which is more nearly in a horizontal plane than in a vertical plane, and thus any 80 tendency of the wheel to rebound when striking inequalities in the roadbed is 85 largely or wholly overcome, since the displacement of the wheel relatively to the axle is, as referred to, nearly in a horizontal direction.

Each of the bumpers 30 is preferably 90 composed as indicated in Fig. 2 of a plurality of thicknesses of resilient material, such, for example, as rubber belting, and the cushions 25 are preferably made up in the same manner, although both the bumpers and cushions may be made of solid resilient material if preferred. The manner of mounting the races for the roller bearings of the wheel in the casting 21 will be best understood by reference to Fig. 4. As 95 shown in this figure, the left hand end of the casting 21 is bored to fit the outwardly projecting lugs formed on ring 22, and this ring is in turn bored to receive and support the roller race 70. The ring 22 has formed 100 on it an outwardly projecting sleeve 71 surrounding the race 70, which sleeve is threaded on its outer end to engage a cap for inclosing the end of the axle. The other end of the casting 21 is bored, preferably to a 105 somewhat larger diameter, to receive the outwardly extending lugs of a second ring 22^a similar to the ring 22, with the exception that it has no outwardly extending flange, and this ring 22^a is in turn bored 110 to receive the race 72 for the other roller bearing of the wheel. The two roller bearings of a wheel of the kind under consideration are usually of different diameter, which accounts for the different diameters of the 115 rings 22 and 22^a. It will also be noted that the boss 23 shown in Fig. 4 projecting outwardly from the casting 21 is inclined somewhat to the axis of the wheel, and that the inner surface of the corresponding cushion retaining member 24 is similarly inclined. This is to facilitate placing the cushions in 120 position and removing them from the hub when necessary, since by this construction it is necessary to move the member 24 but a 125 130

short distance axially before the cushion is released. It will be understood that the same construction is employed in connection with all of the cushions. The construction referred to for mounting the races in the casting 21 provides a ready means by which any standard bearings may be mounted in my wheel construction with a minimum amount of machine work.

The construction of the ring 17 and its inwardly projecting bosses may be better understood by referring to Fig. 5, which shows a similar ring 17^a secured by spokes 44 to the rim 45, the inwardly projecting arms and bosses 29^a and 30^b being similar to the corresponding arms and bosses 29 and 30^a shown in Fig. 1, the principal difference being that the inner ends of the bosses 30^b are beveled instead of being rounded as shown in Fig. 1. In the construction shown in Figs. 5, 6 and 7 the spokes 44 are formed as shown in Fig. 7 with outwardly flanged ends so that in constructing the wheel the inner end of each spoke rests upon and around a projecting lug 46 formed on the outer surface of the ring 17^a and the outer end of each spoke rests around an inwardly formed projection 47 formed in the rim. The rim is preferably put in place by heating it so that it will be expanded somewhat, and for this condition the spokes are placed as indicated in Figs. 5 and 6, and then the ends of the spokes are secured to the rim and ring by some form of welding, preferably by means of the oxy-acetylene flame. As shown in Fig. 10, it is advisable in practice to provide protecting shoes 48 between the members 24^a and 26^a and the cushions 25^a to inclose the otherwise open corners of the cushion. These shoes, it will be understood, retain the cushion in place and prevent it being squeezed out through the corners referred to without in any way interfering with the cushioning action referred to above. The edges of the shoes are preferably thinned down to a sharp edge as indicated to afford no opposition to the slight motion of the cushion relatively to them during the cushioning operation. These protecting shoes are not shown in Fig. 1 for the sake of clearness, and yet it will be understood it is desirable to use them in connection with that construction.

In the modified construction shown in Fig. 3 springs are employed instead of the cushions above described. In this construction the casting 21^b is provided with recesses for receiving the inner ends of the springs 49, which serve as bumpers between the casting 21^b and the arms 29^b extending inwardly from the ring 17^b, the ends of these springs being so conformed that they are normally subjected to torsion tending to rotate the casting 21^b in a direction counter clockwise to the ring 17^b. Similar bumper springs 50

are disposed between the casting 21^b and the bosses 30^c extending inwardly from the ring 17^b. Between each pair of bumper springs 49 and 50 a seat is formed on the casting 21^b for receiving a sliding member 51 provided with outwardly extending arms 52 and 53 having lugs 54 and 55 for engaging and holding in place one of the cushion springs 56 and 57 respectively, the other ends of these springs being engaged and retained by lugs 58 and 59 carried by the sliding member 26^b mounted inside of the ring 17^b and in sliding engagement therewith, and held in place by the arm 27^b projecting from the casting 21^b in a manner similar to the construction described above for the casting 21 and the arms 27. The springs 56 and 57, besides having a suitable initial compression to support the load, are also subjected initially to a torsional stress tending to move the sliding member 51 radially away from the ring 17^b to assist in the cushioning operation. The sliding members 51 and 26^b operate when the axle is subjected either to a load or a turning movement, or both, in substantially the manner that the members 24 and 26 operate as described above, the principal difference being that springs of the kind described are employed instead of the cushions 25. The member 51 is provided with a lug 60 extending into a recess 61 formed in the outer surface of the casting 21^b, the edge of this recess and said lug co-operating to limit the sliding motion that may be imparted to the member 51. While but one complete cushioning construction is shown in Fig. 3, it will be understood that four of said combinations are employed in connection with the complete wheel, and that two of each of the bumper springs 49 and 50 are employed in said complete construction.

In the construction shown in Fig. 11, ring 17^e is similar to the ring 17 in Fig. 1 and operates to perform a similar result. In this construction the metal casting 21^e is provided with four seats for receiving the inner ends of the bumpers 30^e and 36^e, the outer ends of which are engaged by the inner ends of the arms 29^e and 73, respectively. The spaces between the resilient bumpers 30^e and 36^e are filled with triangular blocks 74 of resilient material which are provided with protecting metallic shoes 75. The bumpers 30^e and 36^e are provided with metallic protecting shoes 76 and 77, respectively. The outer surfaces of the shoes 75 are engaged by the inner supporting members 24^e, forming the cushion compartments which compartments are completed by the outer members 26^e. The spaces between the ends of the inner and outer members 24^e and 26^e are incased by the protecting shoes 48^e, which serve to hold in place in the cushion compartments the resilient cushions 25^e.

The axial arms 27^c, which, as above described for the construction shown in Figs. 1 and 9, are rigidly secured to the central casting, engage the outer surfaces of the 5 inwardly extending converging walls of the outer members 26^c and these arms serve as wedge members for moving the members 26^c from each other when the inner member of the hub is moved relatively to the 10 outer member in a radial direction along the vertical axis, as shown in Fig. 11. The arms 73, of which but one is shown in Fig. 11, are provided near their inner ends with wedge shaped surfaces for engaging the outwardly 15 extending diverging walls of the inner members 24^c of the cushion supports so that radial motion of the members of the hub construction relatively to each other along the horizontal axis shown in Fig. 11 20 separates the members 24^c from each other. Any displacement of the members of the hub construction relatively to each other, it will be observed from the above description, produces a compression upon the 25 cushions 25^c, which in turn is communicated to the resilient blocks 74, and by them in turn to the lateral faces of the resilient bumpers 30^c and 36^c, which bumpers are also subjected to radial compression by the 30 arms 29^c and 73. I find in many cases that this combined action of the resilient bumpers is effectively produced by the resilient cushions by the interposition of the resilient triangular blocks referred to. The arms 73 35 are provided with clearance openings 31^c through which the studs 32^c extend for holding the side plates of the hub in place substantially as described above in connection with Fig. 1.

40 In the construction shown in Fig. 12, the operation is in a general way similar to that produced by the construction shown in Fig. 11, the difference being that the triangular blocks 74 of resilient material are omitted 45 and instead the resilient cushions 25^a are extended so as to occupy the combined space of the resilient cushions and triangular blocks shown in Fig. 11. In the construction shown in Fig. 12, the outer cushion supports 26^a are extended from just inside the ring 17^a inwardly toward each other and, when in close proximity to the bumpers 30^a, they extend parallel to each other to form the inclosing lateral walls of the bumper construction. Similarly, the inner supports 24^a 50 are continued from their outwardly diverging ends inwardly parallel to each other to form the lateral supports for the resilient bumpers 36^a. The axial arms 27^a and the inwardly extending arms and bosses 29^a and 78 are substantially of the same construction 55 and operate in substantially the same manner as do the corresponding parts found in the construction shown in Fig. 11. As a result of constructing the cushions as shown

in Fig. 12, it will be observed that any compression of any one of the cushions exerts lateral thrusts upon the adjacent resilient bumpers which tend to equalize all shocks to the greatest possible degree. The protecting shoes 48^a and the studs 32^a are of substantially the same construction and for the same purpose as the corresponding parts shown and described in connection with Fig. 11. In Fig. 12 there is also shown a modified 75 construction for securing spokes 44^a to the ring 17^a. In this construction, outwardly extending hollow studs 46^a are secured to the ring 17^a and these studs are provided with flanges 79 of larger diameter than the outer diameter of the body portion of the studs, which body portion is of a diameter substantially the same as the inner diameter of the spokes 44^a. The flanges 79 are of substantially the thickness of the wall of 85 the spokes 44^a, so that as a result of the parts having substantially the same heat conductivity the fusing of the parts together by the oxy-acetylene flame is facilitated. It will be understood that but one spoke is 90 shown in Fig. 12 for the sake of clearness, but that in practice a plurality of regularly spaced spokes is employed in substantially the manner shown in Fig. 5.

In Fig. 13 there is shown a construction 95 to facilitate assembling the cushions in place, which construction permits giving the cushions any desired degree of initial compression. In this construction the end plates 80 and 81 are supported from the sleeve 100 82, which sleeve may be rotatably mounted upon a stationary axle or rigidly secured to a rotary axle in any desired manner not shown. The outer surface of the sleeve 82 is threaded, as indicated, to receive a taper 105 nut 83 having a conical outer surface which fits the inner surface of the cushion supports 84. The outer surfaces of the cushion supports 84 may be formed substantially as indicated in Figs. 1 and 6 and provided 110 with end walls for engaging the ends of the cushions in substantially the manner shown and described in connection with said figures. I do not limit myself to constructing the supports 84 in this manner, however, 115 as the mechanism shown in connection with this construction for holding the cushion supports in place may be employed for other forms of cushion supports. Sliding plates 85 and 86 are located between the end plates 120 80 and 81 and the cushions to inclose the cushion compartments, and the outer surfaces of the cushions are supported by the cushion supports 87 resting on the inner surface of the hub ring 88 in substantially the 125 manner above described. As a result, the cushions 89 are properly held in place and the inner supports may be moved outwardly to any desired degree by screwing the conical nut 83 into the supports upon the sleeve 130

82, this operation being performed preferably by means of a spanner wrench engaging the holes 90 provided for that purpose. When it is desired to take up any lost motion that may result from wear, it is simply necessary to screw the conical nut 83 somewhat farther into the cushion supports 84, and a key 91 is provided engaging suitable keyways in the outer surface of the 10 sleeve 82 and the inner surface of the nut 83 to hold the nut in desired adjustment. When it is desired to remove the cushions and replace them, the conical nut 83 is unscrewed, the cushion supports 84 are released and the cushions 89 may be readily removed for replacement or repair.

It will be understood, in connection with all of the resilient cushion constructions, that these cushions and the resilient bumpers may be made from any desired resilient material having a proper degree of elasticity and resilience and that the cushions and bumpers may either be formed in solid blocks or built up as desired.

25 It will be understood that I do not limit myself to the specific construction described above in carrying out my invention; for example, the supports for the cushions may be somewhat differently formed if preferred, 30 and the shape of the cushions may be correspondingly changed as long as the supports, the axial arms and inwardly extending bosses coöperate in substantially the manner described to compress the cushions when 35 there is a displacement of the inner and outer members relatively to each other. Throughout the claims I refer to the inner and outer supports each constituting two adjacent walls of the cushion receptacle 40 since the receptacles are shown in the drawings as having four walls, but it will be understood that this phraseology includes other constructions of supports as long as the inner and outer supports together substantially inclose the edges of the cushions. 45 Similarly changes may be made in the other features of my construction without departing from the spirit of my invention.

What I claim is:

50 1. In a vehicle wheel, the combination of inner and outer concentric members forming the hub of the wheel, a plurality of inner supports carried by the inner member, each inner support comprising two adjacent supporting walls for engaging a resilient cushioning member, a plurality of outer supports carried by the outer member, each of the outer supports comprising two other adjacent walls for engaging each cushioning 55 member, and resilient members in the space between said inner and outer supports, the adjacent inwardly extending ends of adjacent ones of said outer supports being inclined at an angle to each other and converging inwardly, and arms extending axi- 60 ally from said inner member for engaging the outer surfaces of said inwardly extending ends.

2. In a vehicle wheel, the combination of inner and outer concentric members forming 70 the hub of the wheel, a plurality of inner supports carried by the inner member, each inner support comprising two adjacent supporting walls for engaging a resilient cushioning member, a plurality of outer supports carried by the outer member, each of the outer supports comprising two other adjacent walls for engaging each cushioning member, and resilient members in the space between said inner and outer supports, the 75 outwardly extending ends of adjacent ones of said inner supports diverging outwardly from each other, and bosses projecting inwardly from said outer member into engagement with the outer surfaces of said outwardly diverging ends.

3. In a vehicle wheel, the combination of inner and outer concentric members forming the hub of the wheel, a plurality of inner supports carried by the inner member, 80 each inner support comprising two adjacent supporting walls for engaging a resilient cushioning member, a plurality of outer supports carried by the outer member, each of the outer supports comprising two other adjacent walls for engaging each cushioning member, and resilient members in the space between said inner and outer supports, the adjacent inwardly extending ends of adjacent ones of said outer supports being inclined at an angle to each other and converging inwardly, arms extending axially from said inner member for engaging the outer surfaces of said inwardly extending ends, the outwardly extending ends of adjacent ones of said inner supports diverging outwardly from each other, and bosses projecting inwardly from said outer member into engagement with the outer surfaces of 85 said diverging ends.

4. In a vehicle wheel, the combination of inner and outer concentric members forming the hub of the wheel, a plurality of inner supports carried by the inner member, each inner support comprising two adjacent supporting walls for engaging resilient cushioning members, a plurality of outer supports carried by the outer member, each of the outer supports comprising two other adjacent walls for engaging each cushioning member, resilient members occupying the space between said inner and outer supports, the adjacent inwardly extending ends of said outer supports being inclined at an angle to each other and converging inwardly, arms extending axially from said inner member for engaging the outer surfaces of said inwardly extending ends, a plurality of resilient bumpers carried by 100 said inner member between adjacent ones of 105 said diverging ends.

said inner supports, and arms projecting inwardly from said outer member between said axial arms for engaging said bumpers.

5. In a vehicle wheel, the combination of 5 inner and outer concentric members forming the hub of the wheel, a plurality of inner supports carried by the inner member, each inner support comprising two adjacent supporting walls for engaging a resilient cushioning member, a plurality of outer supports carried by the outer member, each of the outer supports comprising two other adjacent walls for engaging each cushioning member, resilient members in the 10 space between said inner and outer supports, the outwardly extending ends of adjacent ones of said inner supports diverging outwardly from each other, bosses projecting inwardly from said outer member into engagement with the outer surfaces of said outwardly diverging ends, and resilient bumpers carried by said inner member between adjacent ones of said inner supports, said inwardly projecting bosses being formed 15 to engage said bumpers.

6. In a vehicle wheel, the combination of inner and outer concentric members forming the hub of the wheel, a plurality of inner supports carried by the inner member, each inner support comprising two adjacent supporting walls for engaging a resilient cushioning member, a plurality of outer supports carried by the outer member, each of the outer supports comprising two other adjacent walls for engaging each cushioning member, resilient members in the space between said inner and outer supports, the adjacent inwardly extending ends of said outer supports being inclined at an angle to each other and converging inwardly, arms extending axially from said inner member for engaging the outer surfaces of said inwardly extending ends, the outwardly extending ends of adjacent ones 20 of said inner supports diverging outwardly from each other, bosses projecting inwardly from said outer member into engagement with the outer surfaces of said outwardly diverging ends, resilient bumpers carried by said inner member, and arms projecting inwardly from said outer member between said axial arms to engage alternate ones of said bumpers, said inwardly projecting bosses being formed to engage the intermediate ones of said bumpers.

7. In a vehicle wheel, the combination of inner and outer concentric members forming the hub of the wheel, a plurality of inner supports carried by the inner member, each inner support comprising two adjacent supporting walls for engaging a resilient cushion, a plurality of outer supports carried by the outer member, each of the outer supports comprising two other adjacent walls for engaging each cushion, and

resilient cushions occupying the space between said inner and outer supports, the adjacent inwardly extending ends of said outer supports being inclined at an angle to each other and converging inwardly, arms 70 extending axially from said inner member for engaging the outer surfaces of said inwardly extending ends, said outer supports being movably mounted on the inner surface of said outer member so as to be displaced relatively to said outer member and compress the corresponding cushions for radial movement of said axial arms away from said outer member.

8. In a vehicle wheel, the combination of 80 inner and outer concentric members forming the hub of the wheel, a plurality of inner supports carried by the inner member, each inner support comprising two adjacent supporting walls for engaging a resilient cushion, a plurality of outer supports carried by the outer member, each of the outer supports comprising two other adjacent walls for engaging each cushion, resilient cushions occupying the space between said 90 inner and outer supports, the outwardly extending ends of adjacent ones of said inner supports diverging outwardly from each other, and bosses projecting inwardly from said outer member into engagement with the 95 outer surfaces of said outwardly diverging ends, the inner supports being mounted upon said inner members so as to be capable of motion relatively thereto so that said inner supports are moved relatively to said inner member for motion of said bosses toward said inner member.

9. In a vehicle wheel, the combination of inner and outer concentric members forming the hub of the wheel, a plurality of inner supports carried by the inner member, each inner support comprising two adjacent supporting walls for engaging a resilient cushion, a plurality of outer supports carried by the outer member, each of the outer supports comprising two other adjacent walls for engaging each cushion, resilient cushions occupying the space between said inner and outer supports, the adjacent inwardly extending ends of said outer supports being inclined at an angle to each other and converging inwardly, arms extending axially from said inner member for engaging the outer surfaces of said inwardly extending ends, the outwardly extending ends of adjacent ones of said inner supports diverging outwardly from each other, and bosses projecting inwardly from said outer member into engagement with the outer surfaces of said outwardly diverging ends, said outer supports being movably mounted on the inner surface of said outer member so as to be displaced relatively to said outer member and compress the corresponding cushions for radial movement of said axial arms 130

away from said outer member, the inner supports being mounted upon said inner member so as to be capable of motion relatively to said inner member for motion of said bosses toward said inner member.

10. In a vehicle wheel, the combination of inner and outer concentric members forming the hub of the wheel, a plurality of inner supports carried by the inner member, 10 each inner support comprising two adjacent supporting walls for engaging a resilient cushion, a plurality of outer supports carried by the outer member, each of the outer supports comprising two other adjacent 15 walls for engaging each cushion, resilient cushions occupying the space between said inner and outer supports, the adjacent inwardly extending ends of said outer supports being inclined at an angle to each 20 other and converging inwardly, arms extending axially from said inner member for engaging the outer surfaces of said inwardly extending ends, the outwardly extending ends of adjacent ones of said inner 25 supports diverging outwardly from each other, bosses projecting inwardly from said outer member into engagement with the outer surfaces of said outwardly diverging ends, resilient bumpers carried by said inner member, and arms projecting inwardly 30 from said outer member between said axial arms to engage alternate ones of said bumpers, said inwardly projecting bosses being formed to engage the intermediate ones of 35 said bumpers whereby the bumpers are subjected to compression radially and laterally by displacement of the inner member relatively to the outer member.

11. In a vehicle wheel, the combination of
40 inner and outer concentric members forming
the hub of the wheel, a plurality of in-
ner supports carried by the inner member,
each inner support comprising two adjacent
45 supporting walls for engaging a resilient
cushion, a plurality of outer supports car-
ried by the outer member, each of the outer
supports comprising two other adjacent
walls for engaging each cushion, and resili-
ent cushions occupying the space between
50 said inner and outer supports, the adjacent
inwardly extending ends of said outer sup-
ports being inclined at an angle to each
other and converging inwardly, arms ex-
tending axially from said inner member for
55 engaging the outer surfaces of said inwardly
extending ends, said outer supports being
movably mounted on the inner surface of
said outer member so as to be displaced
relatively to said outer member and com-
60 press the corresponding cushions for radial
movement of said axial arms away from
said outer member, and shoes protecting the
cushions at the ends of said supports and
closing the opening between said ends.

65 12. In a vehicle wheel, the combination of

inner and outer concentric members forming the hub of the wheel, a plurality of inner supports carried by the inner member, each inner support comprising two adjacent supporting walls for engaging a resilient 70 cushion, a plurality of outer supports carried by the outer member, each of the outer supports comprising two other adjacent walls for engaging each cushion, resilient 75 cushions occupying the space between said inner and outer supports, the outwardly extending ends of adjacent ones of said inner supports diverging outwardly from each other, bosses projecting inwardly from said outer member into engagement with the 80 outer surfaces of said outwardly diverging ends, the inner supports being mounted upon said inner member so as to be capable of motion relatively thereto so that said inner supports are moved relatively to said inner 85 member for motion of said bosses toward said inner member, and shoes for protecting the cushions at the ends of said supports and closing the opening between said ends.

13. In a vehicle wheel, the combination of 90
inner and outer concentric members forming
the hub of the wheel, a plurality of inner
supports carried by the inner member, each
inner support comprising two adjacent sup- 95
porting walls for engaging a resilient cush-
ion, a plurality of outer supports carried by
the outer member, each of the outer supports
comprising two other adjacent walls for en- 100
gaging each cushion, resilient cushions oc-
cupying the space between said inner and
outer supports, the adjacent inwardly ex-
tending ends of said outer supports being in-
clined at an angle to each other and converging
inwardly, arms extending axially from 105
said inner member for engaging the outer
surfaces of said inwardly extending ends,
the outwardly extending ends of adjacent
ones of said inner supports diverging out-
wardly from each other, bosses projecting in- 110
wardly from said outer member into engage-
ment with the outer surfaces of said out-
wardly diverging ends, said outer supports
being movably mounted on the inner surface
of said outer member so as to be displaced 115
relatively to said outer member and com-
press the corresponding cushions for radial
movement of said axial arms away from said
outer member, the inner supports being
mounted upon said inner member so as to be
capable of motion relatively to said inner 120
member for motion of said bosses toward
said inner member, and shoes for protecting
the cushions at the ends of said members and
closing the opening between said ends.

14. In a vehicle wheel, the combination of 125
inner and outer concentric members forming
the hub of the wheel, a plurality of inner
supports carried by the inner member, each
inner support comprising two adjacent sup- 130
porting walls for engaging a resilient cush-

ion, a plurality of outer supports carried by the outer member, each of the outer supports comprising two other adjacent walls for engaging each cushion, resilient cushions occupying the space between said inner and outer supports, the adjacent inwardly extending ends of said outer supports being inclined at an angle to each other and converging inwardly, arms extending axially from 10 said inner member for engaging the outer surfaces of said inwardly extending ends, said outer supports being movably mounted on the inner surface of said outer member so as to be displaced relatively to said outer 15 member and compress the corresponding cushions for radial movement of said axial arms away from said outer member, and stops for limiting the motion of said supports relatively to said member.

16. In a vehicle wheel, the combination of inner and outer concentric members forming the hub of the wheel, a plurality of inner supports carried by the inner member, each inner support comprising two adjacent 20 supporting walls for engaging a resilient cushion, a plurality of outer supports carried by the outer member, each of the outer supports comprising two other adjacent walls for engaging each cushion, resilient 25 cushions occupying the space between said inner and outer supports, the outwardly extending ends of adjacent ones of said inner supports diverging outwardly from each 30 other, and bosses projecting inwardly from said outer member into engagement with the outer surfaces of said outwardly diverging ends, the inner supports being mounted upon said inner member so as to be capable of motion relatively thereto so that said inner 35 supports are moved relatively to said inner member for motion of said bosses toward said inner member, the supporting surfaces between said inner member and said inner supports permitting a rocking motion of 40 said inner supports relatively to said member.

17. In a vehicle wheel, the combination of inner and outer concentric members forming the hub of the wheel, a plurality of inner supports carried by the inner member, each inner support comprising two adjacent supporting walls for engaging a resilient cushion, a plurality of outer supports carried by the outer member, each of the outer supports comprising two other adjacent walls for engaging each cushion, resilient 45 cushions occupying the space between said inner and outer supports, the outwardly extending ends of adjacent ones of said inner supports diverging outwardly from each other, and bosses projecting inwardly from said outer member into engagement with the outer surfaces of said outwardly diverging ends, the inner supports being mounted upon said inner member so as to be capable of motion relatively thereto so that said inner supports are moved relatively to said inner member for motion of said bosses toward said inner member, the supporting surfaces between said inner member and said inner supports permitting a rocking motion of said inner supports relatively to said member.

18. In a vehicle wheel, the combination of inner and outer concentric members forming the hub of the wheel, a plurality of inner supports carried by the inner member, each inner support comprising two adjacent supporting walls for engaging a resilient cushion, a plurality of outer supports carried by the outer member, each of the outer supports comprising two other adjacent walls for engaging each cushion, resilient cushions occupying the space between said inner and outer supports, the outwardly extending ends of adjacent ones of said inner supports diverging outwardly from each other, and bosses projecting inwardly from said outer member into engagement with the outer surfaces of said outwardly diverging ends, the inner supports being mounted upon said inner member so as to be capable of motion relatively thereto so that said inner supports are moved relatively to said inner member for motion of said bosses toward said inner member, the supporting surfaces between said inner member and said inner supports permitting a rocking motion of said inner supports relatively to said member.

19. In a vehicle wheel, the combination of inner and outer concentric members forming the hub of the wheel, a plurality of inner supports carried by the inner member, each inner support comprising two adjacent supporting walls for engaging a resilient cushion, a plurality of outer supports carried by the outer member, each of the outer supports comprising two other adjacent walls for engaging each cushion, resilient cushions occupying the space between said inner and outer supports, the outwardly extending ends of adjacent ones of said inner supports diverging outwardly from each other, and bosses projecting inwardly from said outer member into engagement with the outer surfaces of said outwardly diverging ends, the inner supports being mounted upon said inner member so as to be capable of motion relatively thereto so that said inner supports are moved relatively to said inner member for motion of said bosses toward said inner member, the supporting surfaces between said inner member and said inner supports permitting a rocking motion of said inner supports relatively to said member.

20. In a vehicle wheel, the combination of inner and outer concentric members forming the hub of the wheel, a plurality of inner supports carried by the inner member, each inner support comprising two adjacent supporting walls for engaging a resilient cushion, a plurality of outer supports carried by the outer member, each of the outer supports comprising two other adjacent walls for engaging each cushion, resilient cushions occupying the space between said inner and outer supports, the outwardly extending ends of adjacent ones of said inner supports diverging outwardly from each other, and bosses projecting inwardly from said outer member into engagement with the outer surfaces of said outwardly diverging ends, the inner supports being mounted upon said inner member so as to be capable of motion relatively thereto so that said inner supports are moved relatively to said inner member for motion of said bosses toward said inner member, the supporting surfaces between said inner member and said inner supports permitting a rocking motion of said inner supports relatively to said member.

relatively thereto so that said inner supports are moved relatively to said inner member for motion of said bosses toward said inner member, the supporting surfaces between said inner member and said inner supports 70 permitting a rocking motion of said inner supports relatively to said member, said rocking supporting surfaces being tapered to expand and to permit the ready removal of said inner supports.

17. In a vehicle wheel, the combination of inner and outer concentric members forming the hub of the wheel, a plurality of inner supports carried by the inner member, each inner support comprising two adjacent supporting walls for engaging a resilient cushion, a plurality of outer supports carried by the outer member, each of the outer supports comprising two other adjacent walls for engaging each cushion, resilient 80 cushions occupying the space between said inner and outer supports, the adjacent inwardly extending ends of said outer supports being inclined at an angle to each other and converging inwardly, arms extending axially from said inner member for engaging the outer surfaces of said inwardly extending ends, a plate extending from said inner member for rigidly supporting said axial arms, and a removable plate secured to the other ends of said axial arms, said plates and supports serving to inclose said cushions on all sides.

18. In a vehicle wheel, the combination of inner and outer members forming the hub of the wheel and movable radially relatively to each other, outer cushion supports extending inwardly from the outer member, inner cushion supports extending outwardly from said inner member, resilient cushions filling the compartments formed between said supports, and resilient bumpers between said supports outside of said compartments, said supports being movable relatively to said members to compress said cushions and bumpers.

19. In a vehicle wheel, the combination of inner and outer members forming the hub of the wheel and movable radially relatively to each other, outer cushion supports extending inwardly from said outer member, inner cushion supports extending outwardly from said inner member, resilient cushions filling the compartments formed between said supports, resilient bumpers between said supports outside of said compartments, said supports being movable relatively to said members to compress said cushions and bumpers, and wedge members extending from said inner and outer members between the sides of said supports.

20. In a vehicle wheel, the combination of inner and outer members forming the hub of the wheel and movable radially relatively to each other, outer cushion supports ex-

- tending inwardly from the outer member, inner cushion supports extending outwardly from said inner member, resilient cushions filling the compartments formed between 5 said supports, resilient bumpers between said supports outside of said compartments, said supports being movable relatively to said members to compress said cushions and bumpers, said inner supports having outwardly diverging sides and said outer supports having inwardly converging sides, and wedge members extending from said outer member between the diverging sides of said inner supports, and other wedge members 10 extending from said inner member between the converging sides of said outer supports.
21. In a vehicle wheel, the combination of inner and outer members forming the hub of the wheel and movable radially relatively 20 to each other, outer cushion supports extending inwardly from said outer member, inner cushion supports extending outwardly from said inner member, resilient cushions filling the compartments formed between 25 said supports, resilient bumpers between said supports outside of said compartments, said supports being movable relatively to said members to compress said cushions and
- bumpers, wedge members extending from said inner and outer members between the 30 sides of said supports, and projections from said outer member for radially engaging said bumpers, whereby movement of said members relatively to each other compresses said bumpers radially and laterally. 35
22. In a vehicle wheel, the combination of inner and outer members forming the hub of the wheel and movable radially relatively to each other, outer cushion supports extending inwardly from the outer member, inner 40 cushion supports extending outwardly from said inner member, resilient cushions filling the compartments formed between said supports, and resilient bumpers between said supports outside of said compartments, said 45 supports being movable relatively to said members to compress said cushions and bumpers, said inner supports having inner substantially parallel ends laterally engaging alternate ones of said bumpers and said 50 outer supports having inner substantially parallel ends laterally engaging intermediate ones of said bumpers.

In witness whereof, I hereunto subscribe my name this 13th day of April, A. D. 1916. 55

AUGUST J. MEYER.
